United States Patent Office

Des. 210,418

Patented Mar. 5, 1968

210,418

SPECTACLE FRAME OR THE LIKE

Jack Bloch, Leominster, and Vitalino Marchi, Concord, Mass., assignors to Foster Grant Co., Inc., Leominster, Mass., a corporation of Delaware

Filed Dec. 30, 1966, Ser. No. 5,230

Term of patent 14 years

(Cl. D57—1)

FIG.1

FIG.2

FIG.3

FIGURE 1 is a perspective view of a spectacle frame showing my new design.

FIGURE 2 is a front elevation view thereof.

FIGURE 3 is a partial section view taken along lines 3—3 of FIGURE 2.

The side not shown has substantially the same appearance as the side shown.

We claim:

The ornamental design for a spectacle frame or the like, substantially as shown and described.
